United States Patent Office.

MICHAEL FEIGEL, OF NEW Utrecht, NEW YORK.

Letters Patent No. 91,531, dated June 22, 1869.

IMPROVEMENT IN MORTISING-CHISEL.

The Schedule referred to in these Letters Patent and making part of the same.

To all whom it may concern:

Be it known that I, MICHAEL FEIGEL, of New Utrecht, Kings county, and State of New York, have invented a new and useful Improvement in Mortising-Chisels; and do hereby declare that the following is a general description thereof, reference being had to the accompanying drawings, making part of this specification, of which—

Figure 1 is a side elevation;
Figure 2, a rear elevation;
Figure 3, a view of the cutting-end; and
Figure 4, a transverse section.

This invention, relating to an improvement in the class of tools known as mortising-chisels, which are generally used for cutting mortises in wood, for reception of tenons, consists in constructing a chisel with a cutting-blade at its back, so that at each cut of the chisel the fibres of the wood in rear of the chisel will be cut to the depth to which the chisel descends, and on the return of the chisel from the wood, will draw up the chips with it, leaving a clear space in rear of the chisel after each stroke, and making room-way for the next stroke of the chisel, by means of which a greater amount of work can be performed in the same time, and a consequent saving of labor and expense obtained; besides, the fibres of the wood being cut and drawn out of the mortise by my chisel, makes better work than where the fibres are forced or torn from the mortise, as is the case in operating with the ordinary mortise-chisel.

My improved mortising-chisel is particularly intended to be operated by machinery, but it can in like manner be used by hand.

In the accompanying drawings—
A indicates the chisel;
B, the head;
C, the front;
D, the rear;
d, the cutting-end; and
E, the cutting-blade, attached to the rear, D, of said chisel.

This cutting-blade E is forged in one piece with the chisel, and is located near the centre of the back of the chisel. It is slightly curving, and leans to one side, for the purpose of embracing the chips and drawing them out with the chisel. It also has a cutting-edge, a, as shown in the drawings.

I am aware that chisels having cutting-wings at right angles to the cutting-face of the chisel, so as to form three sides of a square, have been used, to which I lay no claim.

I am also aware that curved blades, for forming tenons projecting from the edges of the chisel, have been used, and I do not claim such; but

What I claim as my invention, and desire to secure by Letters Patent, is—

The mortising-chisel A, provided with the cutting-blade E, projecting obliquely from near the middle of the back thereof, and operating as and for the purpose herein specified.

In testimony whereof, I have hereunto set my signature, this 27th day of November, A. D. 1868.

MICHAEL FEIGEL.
